L. HOUGHTON.
Loading Ordnance.

No. 12,629.

Patented Apr. 3, 1855

UNITED STATES PATENT OFFICE.

LUTHER HOUGHTON, OF PHILADELPHIA, PENNSYLVANIA.

IMPROVED MODE OF LOADING RIFLED CANNON.

Specification forming part of Letters Patent No. 12,629, dated April 3, 1855.

To all whom it may concern:

Be it known that I, LUTHER HOUGHTON, of the city and county of Philadelphia, and State of Pennsylvania, have invented a new and Improved Mode of Loading Rifled Cannon; and I do hereby declare that the following is a full, clear, and exact description of the same, reference being had to the annexed drawings, forming part of this specification, in which—

Figure 1 is a longitudinal section of an elongated ball with sabot in position for loading. Fig. 2 is a similar section, showing position and condition of sabot after receiving the explosive force of the charge. Fig. 3 is a section on line $x-x$ of Fig. 2, perpendicular to major axis of ball, showing the manner in which the sabot is compressed.

Similar letters denote the same parts.

The design of my invention is so to load rifled cannon that at the moment of discharge the ball shall receive the rotation due to the grooves of the piece.

The invention consists in loading the ball with its butt resting in the rim of a deep sabot, the caliber of the piece, a space being left between the base of the ball and the bottom of the cavity in the sabot to admit of the sabot being driven forward by the discharge to fill the grooves of the gun and firmly hold the ball.

The operation will be fully understood from the following description and reference to the annexed drawings.

A is an elongated ball, the base B of which rests in the rim R of a sabot, S, the caliber of the piece, the ball and sabot being driven home by a rammer, as shown in red lines, and be-

fore discharge having the relative position shown in Fig. 1, a space, T, being between the bottom of the cavity in the sabot and the base of the ball. At the moment of explosion the force of the expansive gases will, by acting on the base of the sabot, drive it forward on the butt of the ball, and into the grooves of the gun, producing the position relative to the ball shown in Fig. 2 and compressed appearance seen in Fig. 3, the projections p filling the grooves of the piece. The ball being thus firmly wedged in the bore will receive the twist due to the rifling, and will, when it leaves the gun, preserve this rotation on its major axis in the same manner as the expanding balls of smaller fire-arms. The end gained by effecting this rotation in cannon-balls is well known and does not here require discussion, the province of this specification being to set forth the means of producing the rotation.

Disclaiming the sabot as now used, I claim as new—

For loading rifled or grooved cannon, the employment of a deep sabot at the base of the projectile, so as to be driven thereon and into the grooves of the gun at the moment of discharge for rendering said grooves effective in producing the rotation of the projectile, as specified.

In testimony whereof I have hereunto signed my name before two subscribing witnesses.

LUTHER HOUGHTON.

Witnesses:

JOHN L. SMITH,
JAS. D. CLARY.
